UNITED STATES PATENT OFFICE.

WILLIAM MARRETT, OF TOLEDO, OHIO, ASSIGNOR TO THE LIBBEY GLASS COMPANY, OF TOLEDO, OHIO, A CORPORATION OF OHIO.

DESIGN FOR A CUT-GLASS VESSEL.

SPECIFICATION forming part of Design No. 36,277, dated April 7, 1903.

Application filed February 10, 1903. Serial No. 142,812. Term of patent 7 years.

To all whom it may concern:

Be it known that I, WILLIAM MARRETT, a citizen of the United States, residing at Toledo, in the county of Lucas and State of Ohio, ⁵ have invented and produced a new, original, and ornamental Design for a Cut-Glass Vessel, of which the following is a specification, reference being had therein to the accompanying drawings, in which—

Figure 1 is a perspective view of the inverted vessel; and Fig. 2 is a section on line xx , Fig. 1.

The design is applicable to various vessels of cut-glass ware. The outer surface is ornamented by a series of radial cuttings A, intersecting the center a and arranged to form a plurality of groups of tapering ribs B. These ribs are beaded by cuttings b , and the central

rib B' is ornamented by cross-cuttings, as shown. Intermediate the groups of tapering ²⁰ ribs are festoons formed by curved cuttings C C', arranged to form intermediate ribs D D', which are rounded in cross-section.

The leading feature of the design consists in a vessel having the groups of radial cut- ²⁵ tings with the intermediate curved cuttings, forming festoons.

What I claim as my invention is—

The ornamental design for a cut-glass vessel, substantially as described. ³⁰

In testimony whereof I affix my signature in presence of two witnesses.

WILLIAM MARRETT.
